UNITED STATES PATENT OFFICE.

WARWICK HENRY BEANES, OF PETERBOROUGH, ENGLAND.

BAKING-OVEN.

1,368,015.

Specification of Letters Patent.

Patented Feb. 8, 1921.

Application filed June 16, 1920. Serial No. 389,438.

To all whom it may concern:

Be it known that I, WARWICK HENRY BEANES, a subject of the King of Great Britain and Ireland, residing at Westwood 5 Works, Peterborough, in the county of Northants, England, have invented certain new and useful Improvements Relating to Baking-Ovens, of which the following is a specification.

10 This invention relates to baking ovens of the type in which closed steam pipes or tubular heating elements are employed, such pipes or tubes projecting at one end into a fire box or furnace lined with fire-brick or

15 other refractory material.

The object of the invention is to provide for the ready and effective control and regulation of the heat transmission to the various parts of the oven to give the desired uniform or varying temperatures at the said parts as may be required during the baking operation.

The invention comprises the combination with an adjustable baffle or deflector arranged between the respective groups of tube ends in the furnace, of a by-pass flue for which the said baffle or deflector may serve as a damper, the arrangement being such that the said flue is automatically 25 opened and closed by the movements imparted to the baffle or deflector to control and regulate the distribution or flow of the hot furnace gases over the respective groups of tube ends.

30 In one convenient application of the invention to bakers' ovens having two main groups of pipes or tubes for the heating respectively of the top and bottom of the oven, the iron or other baffle or deflector is mounted in a hinged or pivotal manner 35 in the furnace, between the said groups of tube ends projecting therein. A lever or levers or other convenient means are arranged on the exterior of the furnace for 40 imparting the required pivotal or like movements to the deflector.

45 When the deflector is at a vertical position in the furnace, or at such a position as will have no baffling effect on the hot gases flowing from the fire over both groups of tube ends to the ordinary flue in the usual manner, it serves as a damper or closing plate of a by-pass flue which forms a communication between the portion of the furnace

between the upper and lower groups of tube 55 ends and the ordinary or main flue beneath the damper controlling such flue in the usual manner.

When the deflector is swung or moved from the vertical to a horizontal or approximately horizontal position, it serves to baffle or arrest the hot gases and so prevent the same from impinging on the top group of tube ends. By the said movement of the deflector the latter is moved away from the 65 furnace end of the by-pass flue which is thus automatically opened for the escape of the baffled or deflected gases.

In connection with the lever or levers or other devices for moving or adjusting the 70 deflector, means are provided for holding the deflector at various positions between the two extreme positions in order that it may have a varying baffling effect, causing more or less of the gases to pass over the top 75 group of tube ends or to be diverted through the by-pass flue as may be required to give the desired temperature regulation within the oven.

One or more adjustable baffles or deflectors may be employed and be variously arranged to suit the particular grouping of tube ends in the oven furnace.

Referring to the three accompanying sheets of explanatory drawings:— 85

Figure 1 is a sectional side elevation and Fig. 2 a sectional front elevation of the furnace end of an oven, illustrating one manner of applying the invention.

Figs. 3 and 4 are sectional side elevations 90 showing alternative ways of applying the invention.

The same reference letters in the different views indicate the same or similar parts.

As shown at Figs. 1 and 2, between the 95 upper group *a* and the lower group *b* of tubes there is hingedly mounted the baffle or deflector *c*. In this example the openings to the by-pass flue or flues as *d* are in the end walls of the furnace space or area *e*. 100 When the baffle *c* is in the vertical or out of service position shown in the figures, the said flue openings are closed by lateral extensions *c'* at the ends of the baffle. The baffle is brought to the horizontal or full 105 service position by an external hand lever or levers as *f*. The baffle can be retained at various positions by means of a retaining peg

or pegs in association with a fixed quadrant or like bar as *g* having apertures therein to receive the retaining peg.

The ordinary damper controlling the main flue is shown at *h*.

In the example illustrated at Fig. 3 the opening to the by-pass flue *d* is in the rear wall of the furnace space or area *e*, while in the example at Fig. 4 the baffle or deflector *c* is adapted for sliding instead of pivotal movements. In this latter case the opening or openings to the by-pass flues as *d* are closed, when the baffle or deflector *c* is drawn to its out of service position, by plates 15 or extensions as *c'* at the ends of the baffle. When the baffle is pushed fully in, the said extensions are accommodated in apertures in the rear wall of the furnace area.

Having thus described my invention what 20 I claim as new and desire to secure by Letters Patent is:—

1. In baking ovens having tubular heating elements with ends projecting into the fire box or furnace and disposed in groups 25 respectively over and under each other therein, the combination with a by-pass flue form-

ing a communication from the portion of the furnace between the said groups of tube ends and the ordinary or main flue of the furnace, of means for the simultaneous variation of the effective area of the said portion of the furnace and of the extent of the opening of the said by-pass flue, as set forth.

2. In baking ovens having tubular heating elements with ends projecting into the fire box or furnace and disposed in groups respectively over and under each other therein, the combination with a by-pass flue forming a communication from the portion 40 of the furnace between the said groups of tube ends and the ordinary or main flue of the furnace, of an adjustable baffle or deflector disposed in the said portion of the furnace and adapted both for the variation of 45 the effective area of such portion and for the opening and closing of the said by-pass flue, as set forth.

In testimony whereof I have signed my name to this specification.

WARWICK HENRY BEANES.
